TAPE SPOOL CLIP

Clifford Alexander Seckerson, Iver Heath, England, assignor to United-Carr Incorporated, Boston, Mass., a corporation of Delaware

Filed Sept. 8, 1964, Ser. No. 81,622

Claims priority, application Great Britain May 8, 1964

Term of patent 14 years

(Cl. D17—3)

Fig. 1.

Fig. 2.

*Fig. 3.**Fig. 4.**Fig. 5.*FIG. 1 is a perspective of a tape spool clip embodying my new design; and

FIG. 2 is a view in side elevation of the tape spool clip shown in FIG. 1.

FIG. 3 is a bottom plan view of the tape spool clip as shown in FIG. 1;

FIG. 4 is an end elevation of the tape spool clip as shown in FIG. 1; and

FIG. 5 is a top plan view thereof on a reduced scale, the fragmentary broken line showing of the tape spool being for illustrative purposes only.

I claim:

The ornamental design for a tape spool clip, as shown and described.
